UNITED STATES PATENT OFFICE.

CHARLES J. ALLEN, OF SAN JOSE, CALIFORNIA.

OIL-HEATING DEVICE.

1,103,121.

Specification of Letters Patent. Patented July 14, 1914.

Application filed March 10, 1914. Serial No. 823,708.

To all whom it may concern:

Be it known that I, CHARLES J. ALLEN, a citizen of the United States, residing at San Jose, in the county of Santa Clara and State of California, have invented certain new and useful Improvements in Oil-Heating Devices, of which the following is a specification.

My invention relates to an oil heating device, and more particularly for heating that general class of oil known as crude petroleum fuel oil which requires the proper amount of heat in order to have the same flow through the pipes to the burners and there mix and blend with the air and steam as required for a more perfect combustion.

A further object of my invention is to provide an oil heating device of simple and durable construction capable of being used in connection with the air and steam inlets to a burner without the necessity of disturbing the valvular arrangement of the oil heating device or in any manner altering or changing the construction thereof.

A further object is to provide means whereby the temperature of the oil may be ascertained while the same is feeding through the pipes and one in which the oil may be fed to the burners in the required amount, and one in which the live or direct steam from the boiler may be atomized and mingle with the heated oil as the same enters the burners for a more perfect combustion.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

For a full understanding of the invention and the merits thereof, reference is to be had to the following description and accompanying drawing, in which the figure is a front elevation of my device showing, pipes, valves, and other pipe fittings in place as constructed.

Corresponding and like parts are referred to in the following description and indicated in all the views of the drawing by the same reference numerals.

The improved oil heating device forming the subject matter of the present invention,

comprises a main iron steam pipe 1 attached to the upper portion of boilers 2-2^a by controlling valves 3, and three way pipe connections 4. Said main steam pipe 1 is the direct steam pipe and may be of any size required and turned downward by quarter-turn elbow 5, and connecting with T connection at 6 to which is connected steam pipe 7. Pipe 7 is of the same size as pipe 1 and is for the purpose of carrying the direct steam to burners 8 which enter the fire-box door at 9. T connection shown at 10 connected to pipe 7 in front of boiler 2 shows a smaller steam pipe 11 connected thereto to which is connected valve 12, this controlling valve is for the purpose of governing the amount of direct steam to burner 8. Below burner 8 and connected to oil pipe 11^a is oil controlling valve 13, this valve is for the purpose of governing the amount of oil fuel feed to burner 8. Between boilers 2 and 2^a on steam pipe 7 is connected cut-out valve 14, this valve is for the purpose of shutting off the direct steam from burner 8 under boiler 2^a when the same is not in use. In front of boiler 2^a and connected to steam pipe 7 is T connection 15 to which is connected a smaller steam pipe 16, this pipe having a T connection 17 with a larger steam pipe 18. Below the T connection 17 a distance and connected to steam pipe 16 is steam controlling valve 19, this valve is for the purpose of governing the amount of direct steam to burner 8. Below burner 8 and connected to oil pipe 11^a is oil controlling valve 20, this valve is for the purpose of governing the amount of oil fuel feed to burner 8. Said steam pipe 18 having a cut-out valve 21 connected thereto which is for the purpose of shutting off the direct steam from passing through steam pipe 18 when the same is not required. Connected to said steam pipe 18 is quarter-turn elbow 22 which turns the steam pipe 18 downward to which is connected T connection 23 and cut-out valve 24, said valve being connected to main steam pipe 1 by T connection 25. Valve 24 is for the purpose of shutting off the direct steam from passing through pipe 18 to main pipe 1 when the same is not required. Connected to T connection 23 is the extension of steam pipe 18 to which is connected controlling valve 26, this valve is for the purpose of controlling the amount of direct steam required through steam pipe 18 to main steam pipe 1, said

steam pipe 18 being connected to main steam pipe 1 by quarter turn elbow 27, and **T** connection 28. Steam controlling valve 29 is here shown on main steam pipe 1, this valve is for the purpose of admitting direct steam to any further connections that may be made thereto for the same purpose. Controlling valve 30 on steam pipe 7 is also for the purpose of controlling the steam to any addition to said device that may be required, and controlling valve 31 on main pipe 1 is also for the same purpose as valves 29 and 30.

Connected to the upright portion of main steam pipe 1 is controlling valve 32, this valve controls the amount of direct steam required in the lower portion of main pipe 1. At the lower end of said upright portion of main pipe 1 is a four-way connection 33 connected thereto. Connected to the lower portion of said connection 33 is a drip valve 34, this valve is for the purpose of removing any and all water that may accumulate in that portion of main steam pipe 1 from the condensation of steam passing therethrough.

Connected to the lower horizontal portion of main steam pipe 1 is three way **T** connection 35, connected thereto in an upright position is a short piece of main steam pipe 1 connected to said three way **T** connection 35, to which is connected quarter turn elbow 36, connected to said elbow is cut-out valve 37, this valve is for the purpose of controlling the amount of steam required to pass on through steam pipe 1 to three way **T** connection 25 where the same is then controlled by controlling valve 24. Connected to cut out valve 37 in a horizontal position is a short piece of steam pipe 1 to which is connected quarter-turn elbow 38, to which is connected in an upright position a short piece of main steam pipe 1, the same connecting with three way **T** connection 39 which is connected to the lower horizontal portion of main steam pipe 1, thus completing the connection of main direct steam pipe 1 in front of boiler 2 to that in front of boiler 2^a. Connected to the lower portion of three way connection **T** 25 is drip valve 40, this valve is for the purpose of removing any and all water that may accumulate in that portion of main steam pipe 1 from the condensation of steam passing therethrough. Oil pipe 11^a enters the lower portion of main steam pipe 1 at 41, and is carried on through said pipe 1 as far as required. A packing box is shown at 42 which closely fits around oil pipe 11^a and screws into connection 33, this packing box 42 is for the purpose of preventing any leakage of steam or water around oil pipe 11^a at this point. A packing box is shown at 43 which closely fits around oil pipe 11^a and screws into connection 35, this packing box 43 is for the

purpose of preventing any leakage of steam or water around oil pipe 11^a at this point. Connected to oil pipe 11^a are shown thermometers 44, these registers are for the purpose of designating the degrees of heat to which the oil flowing through oil pipe 11^a under pressure is subjected. Oil pressure gage is shown at 45 the same being of the ordinary steam gage type connected to oil pipe 11^a, this gage is for the purpose of designating the pressure to which the oil is subjected at all times. Shut-off valves 46 are shown connected to oil pipe 11^a and are for the purpose of shutting off the oil from passing from one burner 8 to the other when the same is not in use. Union joints are shown at 47 on oil pipe 11^a which are for the purpose of connecting the ends of said pipes together at this point. Packing boxes are shown at 48 and 49 which closely fit around oil pipe 11^a and screw into **T** connections 39 and 28, which are for the purpose of preventing any leakage of steam or water around oil pipe 11^a at these points.

The operation of my device is as follows,—Oil is admitted to pipe 11^a under pressure from an oil pressure tank not shown. The amount of oil required to be fed to burners 8, is governed by valves 13 and 20, oil pressure being shown by pressure gage 45, and the degrees of heat of said oil is shown by thermometers 44. Steam is admitted to direct steam pipe 1 by valves 3. The required amount of steam admitted to the lower portion of steam pipe 1 through which oil pipe 11^a is incased is governed by valves 32 and 21. Direct steam admitted to burners 8 is governed by valves 12 and 19. Condensation of steam in lower steam pipe 1 is drawn off by drip valves 34 and 40.

Having thus described my invention, what I claim as new and desire to secure by Letters Patent, is—

1. In an oil heating device of the character described, the combination with a plurality of steam boilers and oil burners heating said steam boilers of a main steam pipe communicating with said boilers, valves controlling the supply of steam from said boilers to said main steam supply pipe, said steam pipe extending downwardly from the points of communication with said boilers and thence across in front of said boilers, valves by which the direct steam is controlled to the oil burners, oil pipes for carrying the oil through said direct steam pipe to said burners, valves by which the oil is controlled to said oil burners, valves for shutting off the oil and steam from any one of the oil burners when not in use and still continue the use of the other burner and heating device, as and for the purpose described.

2. In an oil heating device, the combination with a plurality of steam boilers and oil

- burners heating said steam boilers, of a main steam pipe communicating with said steam boilers, valves controlling the supply of steam from said boilers to said main steam supply pipe, said steam pipe extending downwardly from the points of communication with said boilers and thence across in front of said boilers, an oil pipe entering the lower portion of said main steam pipe, packing boxes connected to said main steam pipe for the purpose of preventing any leakage of steam or water around said oil pipe where the same passes in and out of said main steam pipe, thermometers connected to said oil pipe by which the degrees of heat of the oil passing therethrough may be designated, a pressure gage by which the pressure on said oil passing through said oil pipe is designated, valves controlling the oil supply to said oil burners, as and for the purpose described.
- 5 35
- 10 which said steam is controlled to said burners, an oil pipe passing through said main steam pipe adapted to heat the oil in said oil pipe, valves by which the flow of oil is controlled to said burners, means for connecting two or more oil burners to the same device without changing the construction thereof, valves for drawing off the condensed water in the lower portion of said main steam pipe, as shown and described.
- 15 40
- 15 20 3. In an oil heating device, the combination with a plurality of steam boilers and oil burners heating said steam boilers, of a main steam pipe communicating with said steam boilers, valves controlling the supply

of steam from said boilers to said main steam supply pipe, said steam pipe extending downwardly from the points of communication with said boilers and thence across in front of said boilers, an oil pipe entering the lower portion of said main steam pipe, packing boxes connected to said main steam pipe for the purpose of preventing any leakage of steam or water around said oil pipe where the same passes in and out of said main steam pipe, thermometers connected to said oil pipe by which the degrees of heat of the oil passing therethrough may be designated, a pressure gage by which the pressure on said oil passing through said oil pipe is designated, valves controlling the oil supply to said oil burners, as and for the purpose described.

In testimony whereof I affix my signature in the presence of two subscribing witnesses.

CHARLES J. ALLEN.
